UNITED STATES PATENT OFFICE.

THOMAS H. FAIRCHILD, OF JONESBORO, TENNESSEE, ASSIGNOR TO DRAPER CORPORATION, OF HOPEDALE, MASSACHUSETTS, A CORPORATION OF MAINE.

TWISTING AND DOUBLING APPARATUS.

1,265,895.

Specification of Letters Patent.

Patented May 14, 1918.

Application filed May 15, 1917. Serial No. 168,668.

To all whom it may concern:

Be it known that I, THOMAS H. FAIRCHILD, a citizen of the United States, residing at Jonesboro, county of Washington, 5 State of Tennessee, have invented an Improvement in Twisting and Doubling Apparatus, of which the following description, in connection with the accompanying drawing, is a specification, like characters on the 10 drawing representing like parts.

This invention relates to a machine for twisting together a plurality of ends and winding the same upon a yarn receiver, and it has for its object to provide a novel 15 device for manipulating the yarn by which the feed of the yarn will be stopped in case the yarn breaks between the yarn receiver and the feed rolls, or in case one strand becomes entangled with an adjacent strand.

20 In accordance with my improvements I employ a yarn guide in the rear of the feed rolls which has two guide eyes, and the ends which are to be doubled or twisted together are fed from the creels through 25 one of the guide eyes, thence between the feed roll and the presser roll (the latter usually merely resting on the feed roll and being driven by frictional engagement therewith), and thence back over the 30 presser roll and through the other guide-eye and thence between the feed rolls and presser rolls and to the yarn receiver. The advantage of this construction is that if the 35 yarn breaks between the feed rolls and the yarn receiver, the broken end will in most cases be picked up by the yarn which passes around the presser roll and will thus be incorporated into the loop which embraces said presser roll and passes through one of 40 the guide eyes instead of being delivered from the feed rolls, and as a result, after the yarn end has made a few turns about the presser roll, the latter will be raised from the feed roll sufficiently to stop the 45 feeding movement, thus preventing any appreciable waste.

In order to give an understanding of my invention, I have illustrated in the drawings a selected embodiment thereof which will 50 now be described, after which the novel features will be pointed out in the appended claims.

In the drawings, Figure 1 is a vertical sectional view of a portion of a doubling

and twisting machine showing my improvements applied thereto;

Fig. 2 is an enlarged plan view showing the feed rolls and illustrating the course which the yarn takes;

Fig. 3 is a view of one form of my improved yarn guide detached from its support;

Fig. 4 is a section on the line 4—4, Fig. 2.

1 indicates the frame of a doubling and twisting machine and 2 is the yarn receiver 65 on which the doubled and twisted yarn is wound. The illustrated embodiment of the invention is a so-called ring-twisting machine, that is, the doubled yarn 3 is led through a traveler 4 which operates on a 70 spinning ring 5 of usual type, that is mounted on the ring-rail 6. The yarn receiver is supported on a positively-driven spindle 7 and usual in devices of this type.

In machines of this nature the yarn ends 75 from the creel are led between two rolls which are in the nature of feed rolls and which operate to draw the yarn from the creel and feed it to the yarn receiver. One of the rolls of the pair (usually the bottom 80 roll) between which the yarn is fed is a positively-driven roll, and the other roll (usually the top roll) merely rests on the bottom roll and is rotated by frictional engagement therewith, the top roll thus acting 85 as a sort of presser roll. In some machines there is only one bottom or feed roll and the presser roll is situated directly above it. In other machines, two positively-driven bottom rolls are employed and the top or 90 presser roll is situated between them and is supported by both of them. It is the latter construction which I have herein shown, and 8 indicates the positively-driven bottom rolls and 9 the presser roll which rests loosely 95 thereon.

The parts thus far described are or may be all as usual in doubling and twisting machines of this type and hence it will not be necessary to further describe them as 100 their operation will be readily understood by those skilled in the art.

In accordance with my invention I employ a double yarn guide situated back of the feed rolls and provided with two separate guide-eyes so arranged that the ends 105 to be twisted together are led through one of the guide-eyes and thence between the

bottom and top rolls, and thence back over the top roll to the other guide-eye and then between the bottom and top rolls again to the yarn receiver. This yarn-guide is shown at 11 and it comprises a piece of wire bent to form a shank 12, a lower guide-eye 13 and an upper guide-eye 14 which is separated from the lower guide-eye. This yarn guide may be secured to any suitable support. I have herein shown it as mounted on the back-bar 15 which is sometimes constructed to have a reciprocatory or traverse motion so that the wear of the yarn will be distributed over a greater surface of the bottom and top rolls. The ends 10 are led through the lower guide-eye 13, thence between the bottom rolls 8 and the top roll 9, then are led back over the top roll 9, as shown at 16, and through the guide-eye 14, and thence are led between the bottom rolls 8 and top roll 9, and thence to the guide-eye 17 in the usual thread-board 18, and thence to the traveler 4. In this way a loop 19 of the yarn is formed around the top roll 9, said loop being held taut by the guide-eye 14.

If in the operation of the device the twisted yarn 3 breaks between the feed rolls 8 and the yarn receiver it is desirable to stop the feed of the yarn until the end can be spliced thereby to prevent waste. The construction herein shown accomplishes this, for if the yarn does thus break on the delivery side of the feed rolls 8, then the broken end will be picked up by the loop of strands that are passing around the top roll 9 and will be carried around with and wound into the loop 19. This loop will thus increase in size and the tension of the loop will increase with each succeeding lap. After a few laps have been wound into the loop 19 the top roll 9 will become clogged so that it will not turn and thus the feed of the yarn will be stopped. The stopping of the feed is thus accomplished simply by the use of my improved yarn-guide and without the necessity of employing any more or less complicated stop mechanism for this purpose.

Another advantage resulting from my improvement is that it prevents waste which would occur when one yarn 3 becomes entangled with an adjacent yarn due to undue slackness in one of the two adjacent yarns. This operation is sometimes referred to as

"doubling". If the yarn 3 should for any reason become unduly slack between feed rolls 8 and the yarn receiver, such slackness will be picked up by the top roll 9 and carried over the latter into the loop 19, thus preventing the occurrence of sufficient slackness in the portion of the yarn between the feed rolls and yarn receiver to cause any entangling between adjacent yarns.

The device is simple in construction and can be easily applied to any doubling or twisting machine, and when in use it has the effect of a stop motion in preventing further feeding of the yarn if the yarn breaks on the delivery side of the feed rolls or if it becomes unduly slack.

While I have illustrated herein a selected embodiment of my invention, I do not wish to be limited to the constructional features shown.

I claim:

1. In a doubling and twisting apparatus, the combination with a rotatable yarn receiver and means to twist and wind yarn thereon, of a feed roll, a top roll loosely resting on and rotated by frictional contact with the feed roll, and a yarn guide situated on the feeding side of the feed roll and having two guide eyes so situated that the yarn which is delivered from both guide eyes passes between portions of the feed roll and top roll that have frictional engagement with each other at substantially the same point whereby if the yarn breaks between the top roll and yarn receiver, the broken end will be caught by and wound in the loop of yarn that encircles the top roll.

2. In a doubling and twisting machine, the combination with a rotatable yarn receiver and means to twist and wind yarn thereon, of a feed roll, a top roll loosely resting on and rotated by frictional contact with the feed roll, a back-bar, and a yarn-guide sustained by the back-bar and having two guide-eyes, one situated above the other, the ends from the creel being carried through the lower guide-eye and thence between the rolls and around the top roll, thence through the upper guide-eye and between the rolls again to the yarn receiver.

In testimony whereof, I have signed my name to this specification.

THOMAS H. FAIRCHILD.
